Patented Feb. 24, 1920.

Inventor
Ilko Harmata

By Adam E. Schatz
Attorney

UNITED STATES PATENT OFFICE.

ILKO HARMATA, OF BOYEL, ALBERTA, CANADA.

CANDELABRUM.

1,331,709.

Specification of Letters Patent. Patented Feb. 24, 1920.

Application filed August 30, 1919. Serial No. 320,877.

To all whom it may concern:

Be it known that I, ILKO HARMATA, a citizen of Poland, residing at Boyel, Province of Alberta, and Dominion of Canada, have 5 invented certain new and useful Improvements in Candelabra, of which the following is a specification.

This invention has for its principal object the provision of means for supporting 10 candles in a vertical position irrespective of varying diameters of the candles.

A further object is to provide a candelabrum of novel design and construction capable of engaging with candle diameters 15 varying considerable in their size and supporting the same in a firm and practical manner.

These objects are attained by the novel construction and combination of parts hereinafter described and shown in the accompanying drawings, forming a material part 20 of this disclosure, and in which—

Figure 1 is a side elevational view showing a candelabrum made in accordance with 25 the invention, parts being broken away in order to disclose the interior construction, and

Fig. 2 is a top plan view of the same parts also being broken away in order to disclose 30 the interior.

Referring to the drawings in detail, the numeral 10 designates the base of a stand having three ornamental supports 11, here shown to simulate the claws of an animal, 35 the tripod base being connected by screws or rivets 12, with a circular plate 13, having a downturned marginal flange 14.

Supported by the flange 14 is a cylindrical casing 15, having engaged at its upper edge 40 a ring 16, having a Z shaped cross-section, having fixed at its upper edge a flat washer-like plate 18, the same having a central opening 19 of considerable magnitude.

Secured in the cylindrical casing 15, immediately above the plate 18, is a filler 20, having a convex upper surface, while secured centrally in the casing 15 is another 45 filler element 21, formed with double convex surfaces and containing an opening 22, substantially uniform with the opening 19, and a third filler plate 23 extends across the upper end of the cylinder, the same having an opening 24.

A plurality of conically wound, helical expansion springs 25 are secured within the

cylinder, their smaller inner end projecting radially toward the center, while the bases of the springs make contact with the interior of the cylinder in the manner indicated. 60

Pivoted by pins 26 in the horizontally disposed annular space of the ring 16 to the flat surface thereof, are a plurality of plates 27, having convexly curved edges 28, and straight backs 29, the inner edges being 65 adapted to make contact with the candle 30 and are normally drawn thereagainst by helically coiled springs 31, one end of which is engaged by the plate and the other to the raised upper flanged portion of the ring 16, 70 the springs holding the pivoted plates in engagement with the candle so as to maintain it central of the casing in a rigid position.

In operation, the several pivoted plates 27 75 are moved outwardly in any convenient manner and the candle inserted so that it comes in contact with the inner end of the coiled springs 25, pressing the candle toward the center whereupon the plates 27 80 are released, the same swinging outward under the washer plate 18, making contact with the surface of the candle holding it against slipping or side movement in a manner which will be clearly apparent. 85

Having thus described my invention what I claim as new and desire to secure by Letters Patent, is—

1. In a candelabrum, the combination with a tripod base, a cylindrical casing 90 mounted thereon, a plurality of spring elements engaged in said casing their inner ends extending radially adapted to make contact with an entered article whereby it may be held in a vertical position there- 95 within, and washers interposed between rows of said springs.

2. In a candelabrum, the combination with a tripod base, a cylindrical casing mounted rigidly thereon, a plurality of conically wound spiral springs secured in said casing, their smaller ends extending toward the center, space elements secured in said casing having openings through the center, a cover secured over said casing, said cover 105 having an opening through which a candle may pass, and a plurality of spring impelled plates adapted to engage with the exterior of the candle forming a yielding support.

3. A candelabrum comprising a base, a hollow cylindrical casing mounted thereon, a cover for said casing, said cover having a 110

central opening, a plurality of spacer elements secured to said casing, said spacer elements having openings corresponding to the openings in the cover plate, a plurality of conically wound springs arranged in upper and lower rows secured to the walls of said casing extending radially therein, a plurality of plates having arcuate faces

pivoted below said cover plate, springs adapted to draw said arcuate plates inwardly forming a partial cover below the main cover and adapted to support a candle when position therebetween. 10

In testimony whereof I have affixed my signature.

ILKO HARMATA.
